SAFE PROTECTING DEVICE

Bertram J. Stevens, Hollywood, Calif.

Application December 19, 1932, Serial No. 647,931

11 Claims. (Cl. 109—6)

This invention relates to devices for protecting locks of the so-called combination type such as are used on safes, vaults, and the like.

As is well known to those familiar with the art, the conventional type of combination lock embodies a lock mechanism which includes the bolt and the operating disks mounted in the door of the safe. The combination disks and the bolt are operated by a spindle which extends through a tube mounted in the safe door and projects outwardly beyond the exterior surface of the door where it is secured to an operating knob, such knob ordinarily being provided with a dial which works in a dial ring mounted on the safe door.

It is the usual practice for unauthorized persons opening safes for the purpose of robbing them of their contents to gain entrance into the lock mechanism either by driving the spindle through the lock or by pulling it therefrom. In driving the spindle through the lock, it is the usual practice to break the knob off the spindle by striking it with a sledge or by cutting it with a saw or torch, and then using a punch or a sledge to drive the spindle through the lock. When the spindle is pulled, a device similar to a wheel puller is placed upon the knob with legs bearing against the safe door, and by means of a screw mechanism, or other suitable means to give the desired mechanical advantage, the knob and the spindle are pulled outwardly thus shearing the threaded connection between the spindle and the lock operating mechanism or breaking the spindle. After the spindle has been removed the lock may be manipulated by means of a wire inserted through the spindle tube.

It is one object of this invention to produce a device for protecting safes against entry, in the manner just described, by providing the lock with a fragile container of obnoxious fluid, such as tear gas, which is arranged so as to be broken, thereby releasing the fluid, in the event an attempt is made to gain access to or to drive the spindle.

I am aware of the fact that attempts have been made to produce devices designed to release an obnoxious fluid when the spindle is driven through the lock, such devices, however, have a disadvantage in that the damage to the safe itself is done before the thief is driven away, and in the event he knows the location of the article which he desires he may, by working rapidly, open the safe and grab the article before the gas or vapors have an opportunity to take effect. Devices of this character have the further disad-

vantage that they are ineffective in preventing the spindle being pulled.

It therefore becomes a primary object of this invention to produce a device of the class described which is designed so as to prevent either the driving or the pulling of the spindle. In other words the container and the means for breaking the same, in the device contemplated by this invention, are of a nature such that the obnoxious fluid must be released if an attempt is made to gain access to the lock either by driving or pulling the spindle.

In a preferred form of my invention, the spindle operating knob is made hollow, and the container of obnoxious fluid is mounted in the hollow chamber of the knob and is rigidly secured to the operating spindle in a manner such that an abnormal pulling force on the knob or the breakage of the knob by striking it with a sledge or by cutting it with a saw or torch is effective to break the container and release the gas. This device is of extremely simple construction, it may be economically manufactured, and can readily be installed on any standard type of combination lock. Furthermore, it does not necessitate the weakening in any way of the insulating properties of the safe door, and the only part which can be broken can be cheaply and quickly replaced. My invention may, however, be embodied in various other forms, all of which may be economically manufactured and easily installed on any standard type of combination lock, and are effective to guard the safe against damage as well as to prevent access thereto.

The details in the construction of certain preferred forms of my invention, together with other objects attending its production, will be best understood from the following description of the accompanying drawings which are chosen for illustrative purposes only, and in which—

Fig. 1 is an elevational view partly in section showing a combination lock equipped with a preferred form of my invention;

Fig. 2 is an enlarged sectional view taken in a plane represented by the line 2—2 of Fig. 1;

Fig. 3 is a sectional view taken in a plane represented by the line 3—3 in Fig. 1;

Fig. 4 is an elevational view partly in section showing a modification of my invention;

Fig. 8 is an elevational view partly in section showing another modification of the invention; and

Fig. 9 is a sectional view taken in a plane represented by the line 9—9 in Fig. 8.

More particularly describing the invention as herein illustrated, reference numeral 11 indicates the door of a safe or the like which is shown as being provided with a lock mechanism 12 which 10 may be of the conventional type and is shown as comprising a case 13, a bolt 14, combination disks and an operating disk, generally indicated in dotted lines at reference numeral 15.

The disks are operated and the bolt is thrown 15 in the conventional manner by means of a spindle 16 which is threaded and keyed to the lock operating mechanism and which extends through a spindle tube 17 mounted in the safe door with its outer end 18 projecting outwardly beyond the 20 outer surface of the door.

The outwardly projecting end of the spindle tube 17 is slotted as indicated at 19 to receive projections 20 formed in an opening through a plate member 21 which I may term a dial ring. The 25 plate member 21 is locked against the outer surface of the door by means of a nut 22 which is mounted on the extending end of the spindle tube 17.

The spindle 16 is shown as being provided with 30 an enlarged hollow end portion 23, such end portion extending beyond the nut 22 and having an open end 24. Reference numeral 25 indicates a frangible container preferably formed of glass which is filled with an obnoxious fluid such as 35 concentrated tear gas and which has an elongated tip 26 extending into the hollow portion 23 and rigidly secured therein by means of a suitable cement indicated at 27.

It will be observed that the enlarged hollow end 40 23 and the elongated hollow tip 26 are formed so that the tip extends inwardly beyond the outer surface of the door. Such a construction prevents the possibility of the criminal sawing through the dial ring 21 behind the major portion of the container 25. The container 25 is enclosed within a 45 hollow knob 28, such knob being provided with a flange 29 which carries the combination dial as shown in Fig. 3. The space between the interior of the hollow knob and the container 25 is filled 50 with a suitable packing indicated at 30 to protect and support the container during normal handling of the safe and normal operation of the door. The hollow knob is secured to the spindle 16 through the medium of a disk 31, the periphery of which is in threaded engagement with 55 the inner portion of the hollow knob and is locked therein by an overturned edge 32. The disk 31 may be formed integrally with the spindle or it may be secured thereto in any suitable manner such as by means of threads thereto as shown.

In order that a pulling force applied to the knob will be effective to break the container before it breaks the spindle or shears the threads in the lock therein, I make the disk 31 of a frangible 65 construction. The short threaded connection between the disk and the spindle may be relied upon to insure the rupture of the disk before breakage in any part of the spindle or in the connection between the spindle and the lock mechanism, but 70 I consider it preferable to also provide an annular recess 33 on the surface of the disk so as to weaken that portion thereof to such an extent that any abnormal pulling force applied to the knob will be effective to shear the disk in the region of the recess in the event the threads do not

shear so that the continued outward movement of the knob and the peripheral portion of the disk will be effective to shatter the container 25. If the knob is struck with a sledge with sufficient force to break it, it obviously must break the container. If the dial plate 21 were sawed through, it would cut the hollow tip 26 and release the fluid in the container. If the knob were cut by a saw or a torch (assuming that the heat would not break the container) at a point behind the plate 31 so that the knob portion could be removed, it would still be impossible to attack the spindle without breaking the container. In other words, the construction is such that the container must be broken in order to gain access to the spindle for either pulling or driving the same.

In the form of my invention shown in Figs. 4 and 5, I show a construction which in all of its essential respects is quite similar to the device just described, and the parts corresponding to those in Figs. 1 to 3 inclusive are indicated by the same reference numerals distinguished with the letter "a".

The spindle 16a, in this form of my invention, differs from that described above in that it is not provided with a hollow end but extends a substantial distance outwardly beyond the exterior of the door, the extending end being received and cemented in a recess 35 formed on the interior portion of a fragile gas container 25a.

The disk plate 31a, in this form of my invention, is secured at its periphery in the hollow knob member 28a and is attached to the spindle through the medium of a thread and key connection indicated at 36.

The plate in this form of my invention, like the one shown in Figs. 1 to 3 inclusive, is provided with a weakened section indicated at 33a.

The form of my invention shown in Figs. 6 and 7 is somewhat different in construction and principle of operation from the form shown in Figs. 1 to 5 inclusive. However, this construction is such that any axial movement of the knob, such as would be imparted thereto by a pulling force, is effective to break a container of obnoxious fluid.

In this form of my invention, the door and lock mechanism, indicated by reference numerals 11b and 12b respectively, may be the same as the lock mechanism described above. The spindle 16b, 125 which extends through the spindle tube 17b, is secured directly to the dial knob 28b which is the conventional construction employed in combination locks.

Mounted on the outer surface of the safe door 130 behind the dial ring 21b and secured thereto by a nut 22b, is a metal plate 40. This plate carries at its lower end, what I may term, a drum or shell member 41 which in turn is provided with a cover member 42 threaded thereto. The upper portion of the cover member 42 is provided with a hollow sheath 43 which projects upwardly in front of the dial knob 28b and is screwed into close relation therewith through the medium of the threaded connection between the cover and the drum.

The inner surface of the cover member is provided with a pocket 44 which is formed with an opening 45 and is slotted as indicated at 46 to provide a weakened section therein. This pocket receives the inner exposed end of a fragile tube 47 which contains the obnoxious fluid. The container 47, which is of elongated construction, is mounted in a sleeve 48 which is threaded into 150

the pocket 44 and is adapted to be inserted through a passage 49 extending through the door.

Pivottally mounted in the cover above the opening 45 is a hammer member 50 which has a head 51 adapted to pass through the opening 45 and pressed downwardly toward the opening by a spring 51. The hammer is held in retracted position by a fragile link 52, preferably made of glass, which projects into the sheath 43 and has its upper end portion secured therein through the medium of a pin 53 extending through a cap 54.

In installing this device, the plate and drum are first mounted on the surface of the door in the obvious manner with the opening in the drum situated in the front of the passage 49 in the safe door. The cover member, with the hammer held in retracted position, is then screwed onto the drum to a point at which the sheath 43 is situated with its upper end in juxtaposed relation with the outer surface of the knob. The sleeve 48 containing the tube 47 is then inserted through the opening 49 and is screwed into place in the cup 44. When the parts are arranged in this manner the sheath 43 must obviously be moved either by turning the cover member or by bending the sheath outwardly in order to gain access to the knob and the pin. If an attempt is made to turn the cover member, the cup and the tube are placed in shear and the cup will break in the weakened section formed by the slot indicated at 46 thus breaking the tube. If the sheath is bent in any manner, the glass link 52 will be broken, releasing the hammer which will be driven by the spring through the opening 45, thus breaking the container of gas.

The drum or shell 41 is provided with openings 55 to permit the escape of gas into the room, and the inner end of the sleeve 48 is provided with an opening 56 to permit the escape of gas into the interior of the safe.

In the form of my invention shown in Figs. 8 and 9, the lock mechanism and door may be the same as that described above. In this form of my invention the outer surface of the door is provided with a ring or collar 60 which may be welded or otherwise secured to the door, the dial ring 21c being mounted on the outer edge of this collar so as to form a chamber between the dial ring, and its associated knob or dial 28c, and the door.

The spindle 16c in this form of my invention is made of a length such that it will extend through this chamber to a point at which it can be secured in a conventional manner to the knob, and is provided with a plurality of fingers indicated by reference numerals 61 and 62 which have pointed ends engaging an annular container of gas indicated by reference numeral 63. This container of gas is mounted in the chamber with its outer surface in substantial engagement with the interior of the collar 60 and is held therein against outward movement by means of projections indicated at 64.

In this form of my invention any inward movement of the spindle will force the fingers 61 into crushing engagement with the fragile container, and any outward movement of the spindle will crush the container between the fingers 62 and the projections 64.

It is to be understood that, while I have herein described and illustrated certain preferred forms of my invention, the invention is not limited to the precise construction as described above, but includes within its scope whatever changes fairly come within the spirit of the appended claims.

75 I claim as my invention:

1. For use in combination with a door: a lock; a lock operating mechanism mounted in said door; an operating knob for said lock operating mechanism; a frangible gas container mounted on the exterior of said door and having a portion thereof extending into the interior of said door; and means operable by axial movement of said knob relative to said door to break said container. 80

2. For use in combination with a door: a lock; a lock operating mechanism including a spindle mounted in said door; a spindle operating knob on the exterior of said door; a frangible gas container mounted on the exterior of said door and having a portion thereof extending into the interior of said door; and means operable by axial movement of said knob relative to said door to break said container, said frangible container being contained within said knob. 85

3. The combination of: a lock; a spindle for operating said lock; a frangible container of obnoxious fluid rigidly mounted on the end of said spindle; and a spindle operating knob mounted on said spindle and enclosing said frangible container, said knob being engaged with frangible means securing same to said spindle. 90

4. For use in combination with a door: a lock; a lock operating mechanism including an operating spindle, the end of which projects beyond the outer surface of said door; a frangible container of obnoxious fluid rigidly mounted on the end of said spindle; a hollow knob member enclosing said container; and a diaphragm plate on the end of said spindle and secured at its periphery in said knob member. 105

5. For use in combination with a door: a lock; a lock operating mechanism including an operating spindle, the end of which projects beyond the outer surface of said door; a frangible container of obnoxious fluid rigidly mounted on the end of said spindle; a hollow knob member enclosing said container; and a diaphragm plate on the end of said spindle and secured at its periphery in said knob member, said diaphragm plate being provided with an annular recess to provide a weakened section therein. 110

6. For use in combination with a door having a lock therein, a lock operating mechanism embodying: a spindle extending through said door and having a recess in its outer end; a frangible container of obnoxious fluid having a hollow tip rigidly secured in said recess; an operating knob enclosing said container; and means securing said knob to the end of said spindle. 115

7. For use in combination with a door having a lock therein, a lock operating mechanism embodying: a spindle extending through said door and having a recess in its outer end; a frangible container of obnoxious fluid having a hollow tip rigidly secured in said recess; an operating knob enclosing said container; and means comprising a diaphragm plate on the end of said spindle and engaging said knob at its periphery. 120

8. For use in combination with a door having a lock therein, a lock operating mechanism embodying: a spindle extending through said door and having a recess in its outer end; a frangible container of obnoxious fluid having a hollow tip rigidly secured in said recess; an operating knob enclosing said container; and means comprising a diaphragm plate on the end of said spindle for securing said knob to said spindle, said diaphragm plate being provided with an annular groove to form a weakened section therein. 125

9. For use in combination with a door having a lock therein, a lock operating mechanism em- 130
